ARMORED MOTOR VEHICLE

Russell E. Bauer, Grosse Pointe, Mich., assignor to Bauer
Ordnance Company, Warren, Mich., a corporation of
Michigan

Filed Jan. 2, 1968, Ser. No. 10,030

Term of patent 14 years

Int. Cl. D12—09

U.S. Cl. D14—3

FIG. 1

FIG. 2

FIG. 3

FIG. 4

FIG. 5

FIG. 6

FIG. 7

FIG. 1 is a front perspective view of my novel, ornamental design for an armored motor vehicle;

FIG. 2 is rear perspective view also showing the right side thereof;

FIG. 3 is a rear perspective view thereof, also showing the left side thereof;

FIG. 4 is a side elevation view thereof;

FIG. 5 is a side elevation view thereof, showing the side opposite to the one shown in FIG. 4;

FIG. 6 is a front elevation view thereof; and

FIG. 7 is a rear elevation view thereof.

The dominant features of my design reside in the portions shown in full lines.

I claim:

The ornamental design for an armored motor vehicle, as shown and described.
